UNITED STATES PATENT OFFICE

1,974,480

MANUFACTURE OF BRIGHT FINISH TINNED MATERIAL

Thomas D. Williams, Garfield Heights, and Harley C. Ralston, Cleveland, Ohio, assignors to The American Steel and Wire Company of New Jersey

Application January 20, 1932, Serial No. 587,832

5 Claims. (Cl. 91—70.2)

This invention relates to the manufacture of bright finish tinned material, such as wire, strip and the like, and has for one of its objects the provision of an improved method of an apparatus 5 for manufacturing such material whereby the spotted or water marked surface often formed on the material when produced by the methods heretofore used is eliminated.

In the methods of manufacture heretofore 10 generally used the hot tinned material was immersed in a water bath immediately after passing from the molten tin, to set the tin and produce a bright finish. The sudden immersion of 15 the hot tinned material in the water bath at times when the temperature is slightly higher than others causes the water to boil or bubble and splash so as to cause particles of water to strike the material before it enters the bath. Particles of water striking the hot tinned surface 20 cause spots or stains, which are highly objectionable. It has been suggested that the temperature of the hot tinned material be regulated by passing it a considerable distance through the atmosphere prior to entering it into the water 25 bath. This, however, is objectionable for the reason that the hot tin coating will oxidize or tarnish prior to its entrance into the water bath and, therefore, prevent the formation of a bright finish.

30 The present method and apparatus provides for regulating the temperature of the material as it leaves the tinning bath and prior to its entrance into the water bath in order to prevent the hot material boiling the water of the bath.

35 In the drawing:

Figure 1 is a plan of a continuous tinning apparatus constructed in accordance with the invention.

Figure 2 is a side elevation thereof.

40 Figure 3 is a detail elevation taken on the line III—III of Figure 2.

Figure 4 is an enlarged elevation of the air cooling chamber or box.

Figure 5 is a sectional elevation through the 45 air cooling chamber or box.

Figure 6 is a fragmentary plan of one of the distributing or baffle plates of the air cooling chamber or box as indicated by the line VI—VI of Figure 5.

50 Referring more particularly to the drawing, the letter A designates a bundle of wire which is mounted on the usual pay-off reel B, which reel is free to revolve as the wire is unwound. Several reels B may be located adjacent the end 55 of the apparatus so that successive bundles of

wire may be joined to form a continuous length of material. The wire or other material is drawn from the reel B through an acid bath in a vat C and then through a flux bath in a vat D. From the flux bath the material passes directly to and 60 through a molten tin bath in a tank or vat E. As the wire or other material passes from the tin bath in the tank E it is drawn through a wipe F of any standard construction, which removes 65 surplus tin from the surface of the material and leaves a thin smooth coating of tin.

As stated before, it has heretofore been the practice to pass the hot tinned material directly from the tinning bath into and through a 70 water bath in order to cool and set the tin coating and provide a bright finish.

The present invention, however, provides an air cooling chamber or box O closely adjacent the exit end of the tinning bath through which the 75 freshly or hot tinned material is passed and cooled to a temperature below that at which it will cause a boiling or bubbling of the water in the water bath.

The air cooling chamber or box O of this invention comprises upper and lower distributing 80 chambers 2 and 3, respectively, and an intermediate work travel chamber 4. The top and bottom walls of the intermediate work travel chamber are formed from perforated plates 10 which serve as baffles and cause an even distribution of the air or other gaseous fluid from the distributing chambers into the work travel chamber. The distributing chambers 2 and 3 are provided with inlet ports 5 and 6, respectively, which are connected by conduits N with the outlet or blower port of a fan L. The fan L is driven by an adjustable speed motor K and is adapted to draw air from the outside atmosphere through a pipe or inlet M and to force said air through the pipes or conduits N to the distributing chambers 90 of the cooling chamber or box O.

As the hot tinned material passes through the travel chamber 4 the forced draft of air or other gaseous fluid through the perforated plates 10 cools the material to a temperature below that 100 at which it will cause a boiling or bubbling of the water in a water bath. The material is passed directly from the chamber or box O into a water bath in a vat or bosh G which finally cools the coated material to a temperature at which it 105 will not readily tarnish in the atmosphere. The finally coated and cooled material passes from the water bath in the vat or bosh G through a wipe H of any standard construction and thence to suitable take-up blocks J.

It will be understood that while we have shown and described a specific construction and arrangement of apparatus for carrying out the improved method of this application, we do not wish 5 to be limited thereto, since many modifications may be made for carrying out the method without departing from the scope of our invention as defined in the appended claims.

We claim:

- 10 1. A tinning apparatus for continuously tinning strip and the like comprising, in combination, a vat containing molten tin, means for wiping the excess tin from the material as it passes from said vat, a cooling chamber adjacent said molten tin in the vat, means for providing a forced draft of gaseous fluid through said cooling chamber to cool the tinned work, and a vat containing water adjacent said cooling chamber and adapted to receive the pre-cooled work from said cooling chamber and reduce its temperature to substantially atmospheric temperature.
- 15 2. A tinning apparatus for continuously tinning wire, strip and the like comprising, in combination, a vat containing molten tin, means for wiping the excess tin from the work, a cooling chamber adjacent said molten tin vat, means for providing a forced draft of air through said cooling chamber to cool the hot tinned material to a temperature below which it will cause a boiling and bubbling of water, and a vat containing water closely adjacent said cooling chamber and adapted to receive the pre-cooled work from said cooling chamber and to finally cool the work to a temperature at which it will not readily oxidize 30 in the atmosphere.
- 20 3. In a tinning apparatus for continuously tinning wire, strip and the like, a vat containing

molten tin and a gaseous fluid cooling box adjacent said vat and adapted to receive the hot tinned work from said vat, said cooling box comprising upper and lower fluid distributing chambers and an intermediate work travel chamber, 80 perforated baffle plates forming the top and bottom walls of said work travel chamber and through which the gaseous fluid is distributed from said distributing chambers, said fluid distributing chambers being each provided with inlet ports, and means communicating with said ports for delivering gaseous fluid under pressure to said distributing chambers.

4. The method of producing bright finish tinned wire, strip and the like which includes 90 passing the material through a bath of molten tin, passing the hot, freshly tinned material through a forced draft of gaseous fluid to set the coating and cool said material to a temperature below which it will cause a boiling and bubbling 95 of water, and then immersing said pre-cooled material in water to finally cool the material to a temperature at which it will not readily oxidize in the atmosphere.

5. The method of producing bright finish 100 tinned material which consists in passing the material through a bath of molten tin, then immediately passing the hot, freshly tinned material through a forced draft of air to set the coating and cool said material to a temperature 105 below which it will cause a boiling and bubbling of water, and then immediately immersing said pre-cooled material in water to finally cool the material to a temperature at which it will not readily oxidize in water
